United States Patent Office

Des. 182,364
Patented Mar. 25, 1958

182,364

VACUUM CLEANER

Ivar Jepson, Oak Park, Ross E. Cornwell, Chicago, and
Robert O. Ernest, Oak Park, Ill., assignors to Sunbeam
Corporation, Chicago, Ill., a corporation of Illinois

Application October 18, 1957, Serial No. 48,153

Term of patent 14 years

(Cl. D9—2)

Fig. 1 is a side perspective view of a vacuum cleaner embodying our new design;

Fig. 2 is an enlarged side elevational view of the vacuum cleaner shown in Fig. 1;

Fig. 3 is a top plan view of the vacuum cleaner of Fig. 2;

Fig. 4 is a front elevational view thereof; and

Fig. 5 is a rear elevational view thereof.

We claim:

The ornamental design for a vacuum cleaner, as shown.
